CLAIM

We claim the ornamental design for a dryer cabinet, substantially as shown.

DESCRIPTION

FIG. 1 is a perspective view of a dryer cabinet design according to the present invention.

FIG. 2 is a front elevation view of the dryer cabinet.

FIG. 3 is a left side elevation view of the dryer cabinet.

FIG. 4 is a right side elevation view of the dryer cabinet; and, FIG. 5 is a top plan view of the cabinet.

Applicant makes no claim to the bottom or rear design of the dryer cabinet.
